UNITED STATES PATENT OFFICE.

FRED S. PEARSON, OF BOSTON, MASSACHUSETTS.

DESIGN FOR A YOKE FOR RAILWAY-CONDUITS.

SPECIFICATION forming part of Design No. 29,241, dated August 16, 1898.

Application filed July 1, 1898. Serial No. 684,983. Term of patent 7 years.

To all whom it may concern:

Be it known that I, FRED S. PEARSON, a citizen of the United States, and a resident of Boston, in the county of Suffolk and State of Massachusetts, have invented a certain new Design for Yokes for Railway-Conduits, of which the following is a specification.

The accompanying drawing illustrates a yoke formed according to my design.

At the bottom of the yoke is a broad flat base *a*, which is slightly curved and extends under the central part of the yoke. On the center of this base is a curved rib *b*. The center of the yoke is pierced with an elliptical opening *c*, which extends from the top to the bottom or base *a*. On each end of the yoke

are projections *d d*, the bottoms of which curve down to the base *a* and have the flanges *e e*, and the tops of which have the flat surfaces *f f* at their outer ends.

The leading feature of my design consists of the broad flat nearly-straight base *a*, extending under the central part of the yoke, and the deep opening *c* reaching to the base *a*.

I claim—

The design for a yoke for railway-conduits, as substantially herein shown and described.

FRED S. PEARSON.
